CANDLE LAMP

Charles J. Rogers, Jr., 707 Jackson, River Forest, Ill.

Filed Aug. 9, 1963, Ser. No. 76,164

Term of patent 14 years

(Cl. D48—2)

FIG. 1 is a perspective view of a candle lamp showing my new design;

FIG. 2 is a side elevational view thereof.

FIG. 3 is a top plan view thereof; and

FIG. 4 is a bottom plan view thereof.

The undisclosed sides are the same in appearance as the sides shown. The dominant features of my design reside in the portions shown in full lines.

I claim:

The ornamental design for a candle lamp, as shown and described.
